DESIGN FOR A NECKLACE

Francois Nazare, New York, N. Y.

Application April 30, 1945, Serial No. 119,316

Term of patent 7 years

(Cl. D45—16)

To all whom it may concern:

Be it known that I, Francois Nazare, a citizen of France, residing at New York city, in the county of New York and State of New York, have invented a new, original, and ornamental Design for a Necklace, of which the following is a specification, reference being had to the accompanying drawing, forming part thereof.

In the drawing

Fig. 1 is a front elevational view of a necklace, showing my new design;

Fig. 2 is a sectional view on the line 2—2 of Fig. 1.

I claim:

The ornamental design for a necklace, substantially as shown.

FRANCOIS NAZARE.
